HIGHWAY GUARD

Joseph E. McCracken, Bethlehem, Pa., assignor
to Bethlehem Steel Company, a corporation of
Pennsylvania

Application April 30, 1937, Serial No. 139,926

7 Claims. (Cl. 256—13.1)

My invention relates to guards such as are installed along the sides of highways and more particularly to those highway guards of the semi-rigid type.

5 The primary purpose of a guard rail is to protect dangerous sections of highways so as to prevent vehicles from accidentally leaving the highways and the guard rail should be of such structure that it will withstand the impact of a 10 vehicle and at the same time reduce to a minimum the damage to such vehicle and to the occupants thereof.

One object of my invention is to provide an improved highway guard structure which will effectively resist impacts transmitted thereto by travelling vehicles coming into contact with the guard rail and thereby prevent said vehicles from leaving the highway and at the same time to provide a structure which will sufficiently absorb 20 the shocks transmitted thereto so that no substantial damage will occur to said vehicles.

Another object of my invention is to provide a structure which is sufficiently rigid so as to be self-sustaining, thereby eliminating the necessity 25 for end tension members, such as springs, anchor rods or anchors, thus effecting a substantial economy in erection and maintenance.

A further object of my invention is to provide a guard rail which presents to the roadway a surface free of projections along its entire length, including joints, thus permitting the vehicle, upon impact, to slide freely and to gradually decelerate, thereby eliminating any possibility of a sudden and disastrous stopping of said vehicle.

35 The novel features of my invention will be more fully understood from the following description and claims taken with the accompanying drawing, in which

Fig. 1 is a side elevation of the road guard structure embodying my invention;

Fig. 2 is a perspective view of a portion of the road guard structure shown in Fig. 1; and

Fig. 3 is a section taken along line 3—3 of Fig. 1 in the direction indicated by the arrows.

45 Referring to the drawing more in detail, I show a road guard structure comprising a plurality of posts or supports 10 having a plurality of metal guard rails 11 mounted thereon. The guard rail 11 as shown in the drawing comprises a plate member having a relatively deep longitudinal corrugation 12 and flat portions 13 and 14. The corrugation 12 engages the supports 10 and spaces the portions 13 and 14 at each side of the corrugation 12 from the supports 10. Corrugation 12 50 also imparts strength to the rail 11 and enables

it to resist shocks due to the impact of vehicles therewith. The corrugation 12 also provides sufficient stiffness to the structure so that the rail will not bow inwardly and form a pocket at the post which would result in the vehicle striking the post and sustaining a substantial amount of damage.

The rails 11 are shown extending substantially from center to center of the supports or posts 10 and are connected in an end to end flush relation by angle members 16 and 17 which are disposed above and below the corrugation 12 and engage the adjoining portions 13 and 14, respectively, of the respective plate members. The rails 11 are preferably connected by placing the 15 vertical legs 18 and 19 of the angle members 16 and 17, respectively, against the rear faces of the portions 13 and 14 of the plate members and securing them together by placing bolts 20 or other suitable fastening means through the openings 21 provided therein. The openings 21 are preferably larger than the shank of said fastening means 20 so as to provide means to permit movement of the rails 11 due to thermal expansion and contraction. A slight clearance is also 25 provided between the ends of the rails 11 to permit expansion thereof.

An elongated slot is provided in the ends of the post engaging portion 15 of the corrugation 12 of the adjoining rails 11, thus forming an opening 22 through which a bolt or other suitable fastening means 23 is passed to attach rails 11 to the posts 10. The opening 22 in the adjoining rails is longer than the diameter of the shank of the fastening means 23 passing therethrough, 30 thus allowing for thermal expansion and contraction of the rails 11. As can readily be seen, the joint thus formed has a surface free of 35 projections which will permit a vehicle impacting therewith to slide along the guard rail structure, 40 and therefore to be gradually decelerated until it is brought under control, thereby eliminating damage to occupants, vehicle and guard rail which invariably occurs when a vehicle is suddenly stopped.

45 The horizontal legs 24 and 25 of the angle members 16 and 17, respectively, are situated in relatively close proximity to the post engaging portion 15 of the corrugation 12, and extend from the rear faces of portions 13 and 14 of the plate 50 member to substantially the opposed face of the post 10. The angle members 16 and 17 in addition to constituting connecting means for adjoining rails 11 also constitute reinforcing means therefor. Upon impact of a vehicle with the 55

rails 11 of the guard rail structure, the angle members 16 and 17 by their engagement with the posts will provide supports for the portions 13 and 14 of the plate member and thereby prevent the rails from collapsing and thus obviate any possibility of the vehicle striking the posts. Due to the angle members being in slidable relation to the post, the rails 11 are permitted to spread transversely to a limited degree upon the initial impact of the vehicle. After impact, the rails will assume their normal shape, and return the angle members 16 and 17 to their original position.

It will readily be seen that one of the advantages inherent in the structure of my guard rail is the ease with which moisture will drain therefrom, thereby avoiding corrosion and prolonging the life of the rail.

While I have shown my invention in but one form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

Having thus described my invention, what I claim as new and desire to secure by Letters Patent is:

1. A highway guard comprising a plurality of spaced supports and rails intermediate said supports, said rails comprising impact receiving portions spaced from said supports and a centrally disposed longitudinal corrugated portion engaging said supports and secured thereto and relatively short members intermediate the support and the rails having their ends terminating adjacent the supports.
2. A highway guard comprising a plurality of spaced supports, rails intermediate said supports, said rails having their end portions in alignment at said supports, said rails comprising relatively deep longitudinal centrally disposed corrugations engaging said supports and spacing the outer portions of the rails adjacent the corrugations from said supports, a flanged member disposed intermediate the said outer portions of said rails and said supports, said flanged member having a flange secured to and cooperating with said outer portions of said rails to retain the rails in facial alignment and having a portion extending substantially to said supports.
3. A highway guard comprising a plurality of supports, intermediate rails having their end portions in alignment at the supports, said rails comprising centrally disposed longitudinal cor-

rugations constituting support engaging means and spacing means for spacing the outer portions of the rail from said supports, and flanged members disposed intermediate the outer portions of said rails and the supports.

4. A highway guard comprising a plurality of supports, rails intermediate said supports, said rails comprising centrally disposed longitudinal corrugations, engaging the supports and spacing the outer portions of the rails from said supports, angle members disposed intermediate the outer portions of said rails and said supports, said angle members having one of their legs secured to and cooperating with the outer portions of said rails to retain said rails in facial alignment, and having the other of their legs extending substantially to said supports, and fastening means cooperating with said corrugations and said supports to retain said rails in assembled relation with said supports.

5. A highway guard comprising a plurality of spaced supports, a plate member intermediate said supports, said plate member having a deep corrugation extending nearly of the face thereof and portions at each side of the corrugation, said corrugation constituting strengthening and support engaging means, and the portions of the plate at the sides of the corrugations being in spaced relation with the supports, and angle members intermediate the support and the plate at each side of the corrugation, each of said angle members extending across the face of a support and having its ends terminating adjacent the edges of said support.

6. A highway guard comprising a plurality of spaced supports, plate members intermediate said supports, said plate members having deep corrugations extending nearly of the face thereof, and portions at each side of the corrugations, said corrugations constituting strengthening and post engaging means, the portions of the plate members at the sides of the corrugations being in spaced relation with the supports, and relatively short members having their ends terminating adjacent the edges of the supports adapted to engage the supports upon impact of a vehicle with the guard.

7. A highway guard comprising spaced supports and rails intermediate said supports, said rails comprising a corrugated portion having the outer surface thereof engaging the supports and spacing the remainder of the rail from the supports, and an angle member intermediate the support and adjacent rails connecting the ends of said rails.

JOSEPH E. McCACKEN.
